UNITED STATES PATENT OFFICE.

WILLIAM L. PAUL, OF SOUTH BEND, INDIANA, ASSIGNOR TO OLIVER CHILLED PLOW WORKS, OF SOUTH BEND, INDIANA.

CULTIVATOR.

1,035,039.

Specification of Letters Patent.

Patented Aug. 6, 1912.

Application filed July 22, 1909. Serial No. 509,050.

To all whom it may concern:

Be it known that I, WILLIAM L. PAUL, of South Bend, in the county of St. Joseph and State of Indiana, have invented certain new and useful Improvements in Cultivators; and I do hereby declare the following to be a full, clear, and exact description of the invention, such as will enable others skilled in the art to which it appertains to make and use the same.

This invention relates to improvements in cultivators and more particularly to an improved disk attachment for shovel cultivator gangs.

The invention consists in certain novel features of construction and combinations of parts as hereinafter set forth and pointed out in the claim.

In the accompanying drawings, Figure 1 is a view of a cultivator showing the application of my improvements thereto, and Figs. 2, 3 and 4 are enlarged detail views.

1, 2 represent two cultivator gangs, each of which comprises a beam, *a*, provided at its rear end with a bracket *b* which projects laterally outward from the beam, and a bracket *5* which projects laterally inward from the beam in advance of the rear portion of the latter from which the bracket *b* projects outwardly. To each bracket *b*, and to each beam *a* intermediate the brackets *b* and *5*, standards *3* are clamped, and with the lower ends of these standards, shovels *4* are connected. Standards *6* are attached to the members *5* of the frames 1—2 by means of clamps *7* and each of these clamps comprises two jaws *8—9* and a clip *10* for securing the clamp to the standard and to the frame member *5*,—the jaw *9* having a seat *11* for the accommodation of the member *5* of the frame. Each standard *6* is bent outwardly at its lower end and this outwardly bent portion is provided at its free end with an integral arm or journal *12* which is disposed in a slightly inclined position. A hub *13* is mounted to rotate on the journal *12* and is provided with a flange *14* to which a disk *15* is secured. A nut or washer *16* is located on the arm or journal *12* and bears against

the outer end of the hub *13*,—said nut or washer being held in place by means of a pin *17* passing through the arm or journal *12* and resting in notches *18* in said washer. The end of the arm or journal *12* and the washer *16* are inclosed by a dust cap *19*. It will thus be seen that two disks, carried by the respective frames 1—2 are disposed to coöperate with each other in forming a furrow or more properly speaking for throwing the earth laterally in opposite directions and that said disks are located between the respective gangs of shovels.

The upper ends of the standards *6* project above the frames 1—2 and are connected by a bar or yoke *20*,—said bar or yoke being attached to the respective standards by means of clamps *21*, each having a tubular portion *22* for the standard. The clamps *21* are secured to the bar or yoke *20* by clips *23* and to the standards *6* by means of set screws *24*. The two disk attachments are thus rigidly tied together but the adjustment of one disk and shovel gang relatively to the other disk and shovel gang can be easily effected.

The cross-bar or yoke *20* may, if desired, be utilized to support foot rests *25*.

In order to properly protect the inner end of each hub *13* and prevent the admission of dust, a cap *26* is provided for the reception of the inner end of each hub and each of said caps is provided with an arm *27* secured to the lower portion of the adjacent standard *6*.

Having fully described my invention what I claim as new and desire to secure by Letters-Patent, is,—

A cultivator comprising two beams, a lateral outwardly projecting bracket at the rear end of each beam, a lateral inwardly projecting bracket on each beam in advance of the outwardly projecting bracket thereof, a standard secured to each outwardly projecting bracket, a shovel carried by each standard, a standard clamped to each beam intermediate of the brackets thereon, shovels carried by said brackets, standards clamped to the inwardly projecting brackets on the

beams, disks mounted at the lower ends of the last mentioned standards, clamps mounted on the upper ends of the last-mentioned standards, and a cross bar secured to said last-mentioned clamps to connect the two disk standards.

In testimony whereof, I have signed this

specification in the presence of two subscribing witnesses.

WILLIAM L. PAUL.
